UNITED STATES PATENT OFFICE.

FARNUM F. DORSEY, OF ROCHESTER, NEW YORK, ASSIGNOR TO NORTH EAST ELECTRIC COMPANY, OF ROCHESTER, NEW YORK, A CORPORATION OF NEW YORK.

IGNITION APPARATUS.

1,317,357.

Specification of Letters Patent. Patented Sept. 30, 1919.

Application filed October 5, 1917. Serial No. 194,969.

To all whom it may concern:

Be it known that I, FARNUM F. DORSEY, a citizen of the United States, residing at Rochester, in the county of Monroe and 5 State of New York, have invented certain new and useful Improvements in Ignition Apparatus; and I do hereby declare the following to be a full, clear, and exact description of the invention such as will enable 10 others skilled in the art to which it appertains to make and use the same.

This invention relates to electric ignition-apparatus for use with internal-combustion engines, and particularly to apparatus of 15 the type in which the flow of current through an induction-coil is controlled by a rotary circuit-controller actuated by connection with the engine.

One object of the invention is to render 20 more simple and direct the electric connections between various parts of the apparatus. Another object of the invention is to render the apparatus compact and simple in construction, and particularly to bring together 25 the induction-coil and the circuit-controller in such a manner as to shorten the connections between these parts, and preferably to eliminate exposed connections between them. Another object of the invention is to 30 produce an arrangement such that various binding-posts, through which the circuit-controller or controllers and the induction-coil are connected with a source of current and with the engine, may be brought together so as to facilitate and simplify the 35 making of the necessary connections, and to reduce the number of parts necessary for the support and insulation of the binding-posts.

To the foregoing ends the invention comprises various features of construction and 40 arrangement of the apparatus hereinafter described, as they are defined in the annexed claims.

In the accompanying drawings Figure 1 45 is a front-elevation of ignition-apparatus embodying the present invention, and Fig. 2 is a side-elevation of the same; Fig. 3 is a side-elevation, in section on the line 3—3 in Fig. 1, but on a larger scale than the latter 50 figure. Fig. 4 is a bottom plan-view of the body of insulating-material forming the cover of the circuit-controllers, together with the metal parts embedded in and supported by the cover; and Fig. 5 is a partial 55 plan-view, showing particularly the primary

circuit-controller and the casing in which it is inclosed.

The invention is illustrated as embodied in ignition-apparatus of the type in which low-tension current, controlled by a primary 60 circuit-controller, is converted to high-tension current in an induction-coil, and the high-tension discharges are distributed among a plurality of spark-plugs by a secondary circuit-controller or distributor. 65

Referring particularly to Figs. 1 and 2, which show its external appearance, the apparatus is inclosed by an integral casing which comprises a part 10, in which an automatic advancing-mechanism (not shown) is 70 inclosed; a part 11, which may be described as a gear-housing, and which partly incloses the gearing through which the circuit-controllers are driven; and a part 12, which incloses the circuit-controllers. Directly above 75 the part 12 is a separate housing 13, which incloses the induction-coil, and between the parts 12 and 13 is interposed a body 14 of insulating material, which constitutes a cover for the circuit-controllers and also a 80 support for all of the binding-posts by which the circuit-controllers and the induction-coil are connected with other parts of the electrical apparatus.

The circuit-controllers are actuated by a 85 vertical shaft 15, which turns in a bearing-sleeve 16 fixed in the gear-housing 11, as shown in Fig. 3. This shaft is turned by helical gears 17 and 19, through which it is connected with a horizontal drive-shaft 18. 90 This drive-shaft is connected with the engine by means of a suitable coupling 62 (Fig. 2). An automatic advancing-mechanism, inclosed in the part 10 in the casing, may be interposed in the connections just 95 described, but as it forms no part of the present invention its construction is not illustrated.

The primary circuit-controller is actuated by a cam 20 fixed on the upper end of the 100 shaft 15. This cam engages a contact-lever 21 which co-operates with a fixed contact 22 in the usual manner, and thus periodically opens and closes the primary circuit. The secondary controller or distributor 105 comprises an arm 23, of insulating-material, fixed to the top of the cam 20 so as to rotate therewith. This arm carries a contact-member 24 which co-operates with a series of stationary contact-members 25, these stationary 110

contact-members being embedded in the substance of the cover 14. The cover is provided with a track-way 26 of suitable material, against which the contact-member 24 slides in its revolution.

The secondary contact-members 25 are connected, respectively, by conductors 27, with four binding-posts 28 mounted on the cover 14, the conductors 27 being embedded in the material of the cover and thus thoroughly insulated. Insulated wires 29 may connect the binding-posts 28 to the spark-plugs in the usual manner, the wires being fixed to the binding posts by cap-nuts 30.

16 The secondary discharges are conducted to the contact-member 24 through a resilient conductor 31, which presses upwardly against a contact-stud 32 fixed in the middle of the cover 14. This contact-stud is connected 29 with the secondary winding of the induction-coil, as will be described.

The induction-coil is shown in Fig. 3. Although it may be of any desired form of construction, it is herein shown as of a peculiar form which, while not claimed as a part of the present invention, is particularly adapted, by reason of its compactness, for use in carrying out the present invention. This coil has a short straight core 33, of 30 which the ends are connected by an endless yoke 34 of suitable magnetic material, thus providing a substantially closed magnetic circuit. Within the yoke and surrounding the core 33 are the usual primary and secondary windings.

The induction-coil is inclosed, as aforesaid, by a housing 13, and owing to the absence of stray magnetism in a coil of the type in question, this casing may be of metal. 40 The coil is secured in the housing by a rod 36 which passes axially through the core and the yoke of the coil. One end of this rod loosely engages an opening in a wall of the housing. The other end of the rod 45 is provided with a screw-threaded head 37, which screws into an opening in the opposite wall of the housing and bears against a washer 38 resting against the yoke.

The cover 14, in addition to supporting the secondary binding-posts, carries also the binding-posts by which the primary current is brought to the circuit-controller and the coil. These binding-posts, 39 and 40, are embedded in the substance of the cover, and 50 the post 39 is connected, by a conductor embedded in the cover, with a tubular sleeve 42 which is also embedded in the cover. The cover is provided with a portion 63 which depends within the casing-member 12 for 55 a sufficient distance to afford a firm support for the sleeve 42, and also to insulate the high-tension contact-members effectively from the metal walls of the casing.

The sleeve 42 co-operates with a connecting-plug 43, which is fixed within the cas-

ing-member 12 and is split, in its upper portion, in order to have a resilient engagement with the sleeve and thus insure a good contact. The plug 43 is insulated from the casing, but is electrically connected with a conductive plate 44, integral with the post 45 on which the contact-member 22 is mounted in the usual manner. Current is thus conducted from the binding-post 39 through the sleeve 42 and the plug 43 to the contact-member 22, and thence to the contact-lever 21. This lever has a flexible connection 46 with a plate 47, which is fixed to but insulated from the casing, and this plate supports a second upwardly projecting contact-plug 48, which co-operates with a sleeve 49 fixed in the depending portion 63 of the cover 14. The sleeve 49 is provided, at its upper end, with a binding-screw 50 by which it is connected with one of the primary terminals 51 of the induction-coil. The other primary terminal is connected, by a binding-screw 52, with the binding-post 40.

Through the means just described the circuit is completed through the primary circuit-controller and the induction-coil, so long as the cover 14 is in place. Whenever it is necessary to have access to the circuit-controllers, for the purpose of cleaning or adjustment, the cover may be removed without disconnecting any of the wires by which the circuit-controllers and the induction-coil are connected with other parts of the apparatus. When the cover is so removed the sleeves and the spring-plugs are temporarily 100 disengaged from each other, but upon replacement of the cover these parts are brought again into co-operative engagement.

One of the terminals of the secondary winding of the induction-coil may be 105 grounded in the usual manner, and the other terminal 53 is connected directly with the upper end of the contact-stud 32. Owing to this arrangement of the parts it will be apparent that the use of an external high-tension conductor between the induction-coil and the secondary circuit-controller is entirely avoided, and the connection between these parts is as short and simple as possible, thus rendering the apparatus rugged 110 and avoiding the danger of loss of energy through faulty insulation.

The primary circuit-controller is shown as provided with a condenser 54 mounted within the casing-member 12 and connected, in the usual manner, with the contact members.

The coil-housing 13 is fixed to the cover 14 so that the relation of these parts is not disturbed when the cover is removed, the 125 coil, casing and cover being always handled as a unit. For this purpose the housing 13 is provided with depending lugs 55 which are fixed to the cover by screws 56. In order to secure the cover in place on the casing 130

12 two fastening-devices are employed, which are readily disengageable to permit removal of the cover. The case 12 is provided with lugs 57 between which bowed 5 spring-members 58 are pivoted. To the upper end of each member 58 a cam-lever 59 is pivoted, these members coöperating, in a manner which will be obvious, with lugs 60 projecting from the sides of the coil-housing 13.

10 By providing sufficient slack and flexibility in the high-tension conductors 29 which are secured to the binding-posts 28, and in the primary conductors 61 which are 15 attached to the binding-posts 39 and 40, it is rendered unnecessary to detach any of these conductors when the cover 14 is released and raised from the casing-member 12 to afford access to the circuit-controllers.

20 It will be apparent that the invention is not limited to use in connection with the particular forms of circuit-controllers and induction-coil illustrated and hereinbefore described, and in general the invention is not 25 limited to the illustrated embodiment thereof, but may be embodied in various other forms within the scope of the following claims.

The invention claimed is:

30 1. Ignition-apparatus comprising: a casing; primary and secondary circuit-controlling means inclosed therein; an integral cover, of insulating-material, removably mounted on and closing said casing; an induction-coil mounted on the outer surface 35 of said cover; a housing covering the induc-

tion-coil and secured to the cover; and connecting means passing through the cover and connecting the induction coil with the circuit-controlling means. 40

2. Ignition-apparatus comprising: a casing; primary and secondary circuit-controlling means inclosed therein; an integral cover, of insulating material, removably mounted on and closing said casing; an induction-coil 45 mounted on the outer surface of said cover; a housing covering the induction-coil and secured to the cover; and connecting-means passing through the cover and connecting the primary and secondary windings of the 50 coil with the circuit-controlling means without externally-exposed conductors.

3. Ignition-apparatus, as in claim 1, comprising primary binding-posts mounted on said cover, and slip-connections, between said binding-posts and the primary circuit-controlling means, engageable and disengageable automatically when the cover is placed and removed. 55

4. Ignition-apparatus, as in claim 1, in which said cover has a body in the form of a substantially flat plate of insulating material with binding-posts for external connections mounted in its exposed surfaces or edges. 60

5. Ignition-apparatus, as in claim 1, comprising disengageable fastening-devices directly connecting said casing and said housing; and independent fastening-devices for securing the housing on said cover. 65

FARNUM F. DORSEY.
